[57] ABSTRACT

Lapidary apparatus for grinding rocks or stones into polished spheres, which are attractive works of art, comprising an automatic sphere grinder with automatic feeder, said apparatus including a grinding cup rotatable about a vertical axis and adapted to receive a work object to be ground into a sphere, a travelling

boom, a pair of legs mounted on said boom and adapted to contact and rotate the work object, said legs contacting the work object on each side of the vertical axis of the cup to hold the work object in the cup, a motor crank arm connected to one end of the boom for reciprocably moving the boom and legs in a direction generally along the longitudinal axis of the boom so as to move the length of the legs over the work object to rotate it about a horizontal axis, a lift member mounted on the other end of the boom adapted to contact a stop member to momentarily lift the legs from the work object to allow the cup to spin the work object to another grinding position, a grit hopper having a feed port, a grit receiving member having an arcuate surface positioned below the feed port a distance such that when in normal position the arcuate surface receives a pile of grit having a positive angle of repose that shuts off the feed port, a shaft rotatably supporting the grit receiving member and having a handle extending downwardly therefrom of sufficient length to be heavy enough to support said arcuate surface in position beneath the feed port, a funnel mounted beneath the grit receiving member and over the work object, an actuating arm mounted on the boom and positioned so as to strike said handle to move the arcuate surface back and forth beneath the feed port to receive and dispense grit material into said funnel, and a water system with a water feed port positioned over the work object for feeding water thereto, said water feed port being positioned away from the funnel tube to prevent water from entering the funnel and clogging it with wet grit.

1
AUTOMATIC GRIT FEEDCROSS-REFERENCE TO RELATED
APPLICATIONS

This application is a division of my patent application Ser. No. 143,799, filed May 17, 1971 now U.S. Pat. No. 3,739,531.

BACKGROUND OF THE INVENTION

This invention relates to lapidary equipment and more particularly concerns a sphere grinder and automatic grit feeder for grinding rocks or stones into polished spheres which are recognized as attractive objects of art.

Lapidaries are people who cut, polish and engrave precious stones or rocks. Lapidaries may do this as a profession, or they may do this as a hobby and may join a lapidary society whose members enjoy working on stones and rocks.

It is believed that many more amateur lapidaries would be grinding rocks and stones into spheres if they did not think that sphere cutting was too difficult, too time consuming, and involved expensive equipment.

The simplest sphere grinder is a rotating cup. Loose grit is applied to the cup and a rock is held in the cup by hand and slowly rotated so that the grit grinds the rock surface into a sphere. However, grinding a sphere by hand involves constant attention and a great deal of time since it calls for rotating the rock by hand against the spinning cup and feeding grit and water to the cup with a paint brush as needed. Such a hand operation may take five to twenty-five hours, or more, before the rock is ground into an acceptable sphere.

For a full description of the operation in hand grinding a sphere, I refer to my article entitled "Sphere Grinding In The Bargain Basement" which appeared in the *TUSCARORA BULLETIN*, a publication of the Tuscarora Lapidary Society, Inc., in the November and December, 1969 issues, such article being hereby incorporated by reference.

Instead of grinding rock or stone into a sphere by this hand method, a lapidary may use a machine. However, conventional machines may cost \$100.00 to about \$400.00. Also, such machines are fairly complicated and may include a pair of facing cutter cups and shafts. Such sphere maker machines are made by Covington Engineering Corp., Redlands, Cal., and by Highland Park Mfg. Co., Inc., S. Pasadena, Cal., for example.

SUMMARY OF THE INVENTION

It is an object of this invention to provide an automatic sphere grinder including an automatic feeder, which apparatus is relatively simple and inexpensive.

The apparatus includes a rotatable grinding cup adapted to receive a work object such as a stone or rock to be ground into a sphere, a travelling boom, a pair of legs mounted on the boom for contacting and rotating the work object, a motorized crank arm for reciprocably moving the boom and contact legs in a direction generally along the longitudinal axis of the boom, a stop member for contacting the end of the boom and lifting the legs away from the work object to allow the rotating cup to spin the work object to another position, and automatic feeder means for feeding a grinding material to the work object, said feeding means including a grit hopper having a grit feed port at

2

the bottom for gravity feed therethrough, a grit receiving element mounted on a shaft and having a top surface positioned beneath said grit feed port for receiving a pile of grit and closing the feed port because of the angle of repose of the grit, a handle extending downwardly from said receiving element shaft and being heavier than the grit receiving element to maintain the receiving element in upright normal position, and an actuating arm mounted on the boom and adapted to contact said handle during reciprocation of said boom to rotate said receiving element shaft to move the receiving element and dump the grit from its top surface onto the work object.

15 BRIEF DESCRIPTION OF THE DRAWINGS

Objects and advantages of this invention, including its simplicity and economy, as well as the ease with which it may be adapted for use with existing equipment, will become apparent hereinafter and in the drawings, in which:

FIG. 1 is a view in side elevation of an automatic sphere grinder with automatic feeder constructed in accordance with this invention, with parts being shown in section in order to better illustrate the invention;

20 FIG. 2 is a view in top plan taken as indicated by the lines and arrows 2-2 which appear in FIG. 1;

FIG. 3 is a partial view in side elevation, similar to FIG. 1, but showing a later stage in operation with its lift lever resting on a stop member so as to release its legs from contact with the work object;

25 FIG. 4 is a view in section taken as indicated by the lines and arrows 4-4 which appear in FIG. 2;

FIG. 5 is a view similar to FIG. 4 but shows the stage 30 of operation of FIG. 3 whereas FIG. 4 shows the stage of operation of FIG. 1;

FIG. 6 is an enlarged view of a portion of the automatic grit feeder showing how the grit forms a conical pile, because of the angle of repose of the grit, to shut 35 off the grit feed port;

FIG. 7 is a view of a rough rock or stone which is to be ground into a sphere;

FIG. 8 is a view of the rock after it has been sawed 40 into a more or less cube shape with the corners sawed off; and

FIG. 9 shows the rock in its final form after being 45 ground and polished into a sphere by the apparatus of this invention.

50 DESCRIPTION OF THE PREFERRED
EMBODIMENT

Although specific terms are used in the following description for clarity, these terms are intended to refer only to the structure shown in the drawings and are not intended to define or limit the scope of the invention.

Turning now to the specific embodiment of the invention selected for illustration in the drawings, there 55 is shown lapidary apparatus for grinding rocks or stones into polished spheres comprising an automatic sphere grinder 11 which includes an automatic grit feeder 13. Sphere grinder 11 includes a rotatable grinding cup 15 which is mounted on a vertical shaft 17 supported on table top 19 by support member 21. Shaft 17 is driven by pulley 23, belt 25, and pulley 27 on drive shaft 29 of cup motor 31 mounted on the bottom of table top 19.

Grinding cup 15 is adapted to receive a rock or work object 33 to be ground into a sphere.

A travelling boom 35 includes a central member 37 attached at one end to two side members 39, and a lift lever 41 attached to side members 39 by bolt and wing nut 43 which permits lift lever 41 to be adjusted relative to side members 39. Lift lever 41 is adapted to contact a stop member 45 mounted on table top 19.

A motor 47 is supported on table top 19 by bracket 49. Motor crank arm 51 is positioned in a hole 53 in the end of central member 37 of boom 35 so as to reciprocate boom 35 in a direction substantially along the axis of the boom.

Extending outwardly from side members 39 are square mounting blocks 55 which support circular mounting blocks 57 that contact legs 59 having ends inserted in radial holes in blocks 57. Legs 59 are provided with rubber tubes 61 for better contact with the surface of work object 33. bolts and wing nuts 63 connect blocks 55, 57 together, and the legs 59 may be repositioned easily to accommodate different size rocks by turning back on wing nuts 63 to release the legs from mounting blocks 57, rotating blocks 57, and retightening wing nuts 63.

Splash pan 65 is mounted on table top 19 around spinning cup 15 in order to catch any splashing of the grinding mixture being used to grind work object 33. A drain pipe 67 extends downwardly from splash pan 65 through table top 19.

Automatic grit feeder 13 includes a grit hopper 71 mounted above work object 33 by horizontal support member 73 bracketed to slotted vertical support arm 74 which is connected to vertical support member 75 by bolt and wing nut 76, with the bolt passing through a vertical slot in support arm 74. Grit hopper 71 has a grit feed port 77 at its bottom for gravity feed of the grit therethrough.

A grit receiving element 79 is positioned beneath grit feed port 77 for receiving a pile 81 of grit which closes feed port 77 because of the angle of repose of the grit. The pile 81 of grit forms a cone shape with the apex of the cone at the grit feed port 77 and the sides of the cone sloping downwardly and outwardly therefrom.

Grit receiving element 79, in the preferred form of the invention, is made of wood and has the shape of a pie segment which is mounted on a shaft 33 extending through a grit funnel 85 suspended from horizontal support member 73 by straps 87. Grit receiving element 79 has an arcuate top surface for receiving the grit, and shaft 83 has a handle 89 extending downwardly therefrom which is of sufficient length so as to be heavy enough to support grit receiving element 79 in normal upright position beneath feed port 77.

Grit receiving element 79 is actuated to dump pile 81 of grit onto work object 33 by an actuating arm 91 mounted on boom 35. Arm 91 contacts handle 89 during reciprocation of the boom to thereby rotate receiving element 79 about shaft 83 to dump the grit.

Funnel 85 is positioned around and beneath grit receiving element 79 and includes a cone-shaped body 93 with a tube 95 extending downwardly from the cone apex and terminating in a funnel feed port 97 above work object 33 and cup 15.

Automatic grit feeder 13 also includes a water reservoir 99 positioned above funnel feed port 97, and a gravity feed water tube 101 extending from water reservoir 99 to a position adjacent to but spaced away

from funnel feed port 97 so that the water contacts the dumped grit after it passes through the funnel feed port 97, thereby preventing water entering funnel feed port 97 and clogging the funnel tube 95 with wet grit. Water tube 101 is provided with a valve 103 in order to regulate the flow of water.

In grinding a stone into a sphere by hand, the lapidary holds the stone in his hand and moves it against the edge of a rotating cup, adding a gritting paste made of carborundum or silicon carbide and water between the edges of the rotating cup and the stone. This work takes hours to cut a stone into a sphere.

In operation of the present invention, the stone or work object 33 is placed in spinning cup 15 and is rotated about a horizontal axis by legs 59 of boom 35 which, in the preferred embodiment of the invention, has a nine inch stroke imparted to it by crank arm 51 of motor 47. When crank arm 51 reaches the horizontal position illustrated in FIG. 3, lift lever 41 on boom 35 contacts stop member 45 which prevents further downward movement of lift lever 41 and lifts legs 59 away from the top of work object 33, thereby allowing cup 15 to spin stone 33 to another position. As crank arm 51 continues in its travel, legs 59 return into contact position on top of the newly positioned work object 33 and rotate the work object around a horizontal axis, thus moving the surface of work object 33 into contact with the edges of spinning cup 15 and the abrasive grit which grinds the surface of the stone. In operation of automatic grit feeder 13, the grit in hopper 71 pours through feed port 77 to form a pile 81 on the upper surface of grit receiving element 79. The pile 81 is in the form of a cone in accordance with the angle of repose of the grit, and when the pile grows big enough the cone of grit jams the exit port 77 to prevent more grit from passing therethrough. Accordingly, feed port 77 deposits a limited amount of grit on the top surface of grit receiving element 79 which rotates with shaft 83 when handle 89 is actuated by actuating arm 91 of boom 35. As grit receiving element 79 moves, the grit pours through feed port 77 to pour a continuous band of grit on the upper surface of receiving element 79, and the grit is dumped off this upper surface as element 79 is moved in a reciprocable motion.

One of the advantages of the automatic grit feeder 13 is that it feeds abrasive material and yet the abrasive material does not wear out the parts of the grit feeder because there are so few moving parts. In other words, there is no wearing surface in contact with the abrasive material.

It has been found that 400 grit fine silica does not work in automatic grit feeder 13 because it has a negative angle of repose and does not pour through grit feed port 77 which has a 1/32 inch diameter. However, 200 grit silica and coarser grits work fine in automatic grit feeder 13.

Legs 59 are easily removable from mounting blocks 57 by turning back on the wing nuts 63 and should be removed to clean the coarse grit therefrom before going on to a finer grit. Also, rubber tubes 61 should be replaced so that each size grit has its own rubber tubes, thereby avoiding grit of different sizes being imbedded in the rubber and interfering with the progressive fine grinding of the work object.

Legs 59 may be opened and closed to fit the size of the work object 33 by rotating the position of mounting

blocks 57 before clamping them in place by turning down on wing nuts 63.

Also, grit feeder support arm 73 is movable vertically because it is fastened to a vertical arm 74 that is vertically slotted and may be raised and lowered and then clamped in place by bolt and wing nut 76.

I claim:

1. An automatic grit feeder comprising a grit hopper having a grit feed port at the bottom for gravity feed therethrough, means for closing said grit feed port automatically when a desired portion of said grit has fed through said feed port, said port closing means including grit receiving means positioned beneath said feed port for receiving said grit and forming a pile of grit thereon until the pile reaches such height that it closes said feed port, means spacing said receiving means away from said feed port a desired distance so as to form a pile of grit having the desired amount of grit, and means for actuating said grit receiving means to dump said pile of grit and open said grit feed port said grit receiving means being exposed and including a grit receiving element mounted on a shaft located below the grit feeding port.

2. The automatic grit feeder of claim 1 wherein said grit receiving means comprises a grit receiving element mounted on a shaft and having a top surface for receiv-

ing the grit, a handle extending downwardly from said shaft, said handle being heavier than said grit receiving element to maintain the receiving element in upright normal position, and said actuating means is adapted to contact said handle to rotate said receiving element shaft to move the receiving element and dump the grit from its top surface.

3. The automatic grit feeder of claim 2 including means for feeding water to mix with the dumped grit.

4. The automatic grit feeder of claim 2 including a funnel positioned around the grit receiving element for funneling the dumped grit to a desired location, said funnel including a cone-shaped body with a tube extending downwardly from the cone apex and terminating in a funnel feed port.

5. The automatic grit feeder of claim 4 including a water reservoir positioned above the funnel feed port, and a gravity feed water tube extending from the water reservoir to a position adjacent to but spaced away from the funnel feed port so that the water contacts the dumped grit after it passes through the funnel feed port, thereby preventing water entering the funnel feed port from clogging the funnel tube with wet grit.
